UNITED STATES PATENT OFFICE.

WILLIAM GREILICH, OF BROOKLYN, NEW YORK.

SOLE FOR SHOES.

1,194,732.

Specification of Letters Patent. Patented Aug. 15, 1916.

Application filed December 31, 1915. Serial No. 69,646.

To all whom it may concern:

Be it known that I, WILLIAM GREILICH, a citizen of the United States, and residing in the borough of Brooklyn, county of 5 Kings, State of New York, have invented certain new and useful Improvements in Soles for Shoes, of which the following is a specification.

The present invention relates to an improved sole for shoes, and particularly a sole for bathing, tennis, or other such shoes.

Heretofore, soles for bathing-shoes have generally been made of canvas or other heavy wear-resisting material, and the 15 edges were bound with tape to prevent raveling. After very little wear, the tape would become loose, with the result that the exposed edge of the canvas would ravel, and the shoe would be ruined for further 20 use. Because of the inexpensive nature of such shoes, these soles have been extensively used with the above unsatisfactory results, but it has not been practicable to employ such canvas soles in tennis, gymnasium or 25 other shoes of a more expensive nature and requiring greater service, than bathing-shoes.

It is an object of the present invention therefore, to provide an improved canvas sole, the edges of which will be so permanently and durably bound as to remain intact until this sole is worn through, and with which superior bathing-shoes may be provided, and also because of its increased 35 durability and flexibility, the sole may be advantageously used for tennis, gymnasium, athletic shoes, etc., with better results than with the present form of rubber or leather soles. The binding edges according to my 40 invention, will be so constructed as to form an integral part of the sole, and being impervious to water, will make the shoe waterproof to a high degree.

With these and other objects in view, my 45 invention is shown in the accompanying drawings, and will be hereinafter more fully described with reference thereto, and finally pointed out in the claims.

In the drawings: Figure 1 is a perspective view of the canvas sole before the application of the binding edge thereto. Fig. 50 2 is a plan view of the completed sole. Fig. 3 is a sectional view thereof. Fig. 4 is a bottom plan view of a slightly modified 55 form of construction. Fig. 5 is a top plan view of the same. Fig. 6 is a sectional view

thereof. Fig. 7 is a bottom plan view of a further modified form of construction, and Fig. 8 is a sectional view thereof.

Similar reference characters indicate corresponding parts throughout the several figures of the drawings.

Referring to the drawings, my improved sole is constructed of a plurality of layers of canvas 10, or other suitable wear-resisting material, cemented together by rubber or the like 11. In this form, a binding strip of rubber 12 is placed about the edge of the canvas, and suitable pressure is applied thereto, so that all of the ends or ravelings 65 of the various layers of canvas are firmly embedded in the rubber. The sole is then baked in the customary manner, whereupon the rubber becomes permanently welded to the canvas. The sole thus formed, is entirely flat and smooth, highly resistant to 70 wear, remaining intact until worn through, flexible, impervious to water and lends itself readily to the uses intended.

In Figs. 4 to 6, I have shown a slightly 80 modified form of construction in which the manufacture of the sole is greatly facilitated. This sole comprises a canvas body 10 similar to the form illustrated in Fig. 1 and composed of several superposed layers 85 of canvas cemented together. A binding strip 12 is formed about the edge, and a thin rubber sheet 13 is placed on the under side of the canvas body portion 10. The method of forming this rubber sheet and binding edge on the canvas body is as follows: The canvas body portion 10 is placed in a mold and a rubber sheet is placed over the same, so that its outer edges extend beyond the edges of the canvas portion. This 90 sheet is then molded upon the canvas so that the outer edges encompass the edges of the canvas and form a binding edge, and the sole is then vulcanized in the usual manner. By this method the resulting binding 95 edge is smooth and uniform, and the manufacture of the sole is greatly facilitated. Any desired configuration such as cross linings, trade-marks, etc., may be readily placed upon the rubber sole during the process of molding and vulcanization.

This rubber under sole adds materially to the appearance of the shoe, and somewhat to the life thereof, although its primary purpose is to facilitate the manufacture. For this reason the same may be made very thin, and therefore at small ex-

pense. After a short time this rubber sheet will wear out but the rubber binding edge will remain intact and preserve the sole during the entire life thereof.

5 In the form illustrated in Figs. 7 and 8, I have provided a continuous groove 14 extending around the outer portion of the sole, for the purpose of securing the sole to the upper part of the shoe. In this way the 10 surface of the sole is entirely smooth.

I have illustrated preferred and satisfactory forms of my invention, but it is obvious that changes may be made therein, within the spirit and scope thereof as defined 15 in the appended claims.

I claim:

1. A sole for bathing shoes, outing shoes and the like comprising a structural body composed of superposed layers of canvas 20 cemented one to another and a marginal border of soft rubber surrounding said canvas layers, the marginal fibers of said lay-

ers being embedded in said border and one of the canvas layers being exposed on the upper side of said sole, said parts being vul- 25 canized together.

2. A sole for bathing shoes, outing shoes and the like comprising a structural body composed of superposed layers of canvas cemented one to another, an under layer of 30 rubber, and a marginal border integral with said under layer and surrounding said canvas layers, the marginal fibers of said layers being embedded in said border and one of the canvas layers being exposed on the 35 upper side of said sole, said parts being vulcanized together.

In testimony that I claim the foregoing as my invention, I have signed my name in presence of two subscribing witnesses.

WILLIAM GREILICH.
